UNITED STATES PATENT OFFICE.

JAMES EDWARD PURDY, OF NEW YORK, N. Y.

NECK-YOKE.

SPECIFICATION forming part of Letters Patent No. 402,193, dated April 30, 1889.

Application filed August 17, 1888. Serial No. 282,964. (No model.)

To all whom it may concern:

Be it known that I, JAMES EDWARD PURDY, a citizen of the United States, residing at New York, in the county of New York and State of New York, have invented a new and useful Improvement in Neck-Yokes, of which the following is a specification.

The invention relates to an improvement in neck-yokes.

10 The object of the present invention is the production of a neck-yoke center of simple and inexpensive construction, capable of adjustment to suit any sized yoke, and also capable of withstanding great wear without increasing the size of the tongue-opening.

15 The invention consists in the novel combination and arrangement of parts hereinafter fully described, illustrated in the accompanying drawings, and pointed out in the claims 20 hereto appended.

25 In the drawings, Figure 1 is a view of a neck-yoke center constructed in accordance with this invention and illustrating the manner of securing it to the yoke. Fig. 2 is a central vertical longitudinal sectional view of Fig. 1. Fig. 3 is a perspective view of the clamping-plates, which render the neck-yoke center adjustable to any sized yoke.

30 Referring to the drawings, A designates the top piece, A' the bottom piece, and A² the loop of a neck-yoke, which portions are integral and constructed of a single piece of leather that is bent in the middle to form the loop A². The size of the loop A² is regulated 35 by clamping-plates B and B', which adapt the neck-yoke center to be employed upon any sized yoke C, and will hereinafter be more fully described. The neck-yoke center has a tongue-opening, A³, which is prevented 40 from stretching and becoming too large for use by a metal ring, D, and re-enforcing pieces E and E', that are secured together and to the top and bottom pieces, A' and A², by stitching.

45 The metallic ring D preserves the shape of the tongue-opening, and has its outer circumference beveled, thereby causing the neck-yoke center to be bulged out and increased in thickness around the tongue-opening A², 50 the point which is subjected to the most wear and strain.

The re-enforcing piece E is of the same length and shape and is bent into the same form as the loop A² and the top and bottom pieces A and A', while the re-enforcing pieces 55 E' conform to the configuration of the top and bottom pieces.

In cutting the lower layers of leather to provide the tongue-opening, portions F are formed by not entirely separating the leather 60 which is forced up through the tongue-opening A³ to receive the wear. These wear-pieces F, when the neck-yoke is in use, lie beneath the tongue and materially increase the durability of the neck-yoke center. 65

70 The clamping-plates B and B', which render the loop A² adjustable, are constructed of suitable metal and clamped together and around the neck-yoke center by nuts G and bolts H, which pass through the said plates 75 and the neck-yoke center. The plate B has its ends b bent at right angles to fit around the edges of the neck-yoke center.

75 The clamping-plate B' also has its ends b' bent at right angles, and they are provided with recesses b², which receive the ends b of the other clamping-plate, B. The ends b' of the clamping-plate B' are provided with curved flanges b³, which fit up against the yoke C and prevent the same turning and 80 wearing the neck-yoke loop A².

85 From the foregoing description and the accompanying drawings the construction, operation, and advantages of the invention will be readily understood.

Having thus described the invention, I claim—

1. The neck-yoke center herein described, provided with clamping-plates to regulate the size of the yoke-loop and adapt the neck-yoke 90 center to any sized yoke, one of said plates being provided at its ends with flanges which fit against the yoke and hold the same, substantially as and for the purpose described.

2. The neck-yoke center herein described, 95 provided around the tongue-opening with a metal ring having beveled edges, whereby the neck-yoke center is bulged out and increased in thickness around the tongue-opening, substantially as described.

100 3. The herein-described neck-yoke center, having the wear-pieces in the tongue-opening

and the beveled ring surrounding said opening, and provided with clamping-plates to regulate the size of the yoke-loop, one of said clamping-plates having at its ends flanges, 5 which fit against the yoke and hold the same, substantially as described.

4. The neck-yoke center herein described, provided in the tongue-opening with wear-pieces, formed integral with the leather at the bottom of said opening, and pushed through

the same to receive the wear from the tongue, substantially as described.

In testimony that I claim the foregoing as my own I have hereto affixed my signature in the presence of two witnesses.

JAMES EDWARD PURDY.

Witnesses:

JAMES E. BROWN,
JOHN F. JACKSON.
